UNITED STATES PATENT OFFICE.

BENJAMIN CAVEN BARTLEBAUGH, OF WHEELING, WEST VIRGINIA.

GAS-BURNER.

1,153,013.

Specification of Letters Patent.

Patented Sept. 7, 1915.

Application filed April 29, 1915. Serial No. 24,835.

To all whom it may concern:

Be it known that I, BENJAMIN C. BARTLEBAUGH, a citizen of the United States, residing at Wheeling, in the county of Ohio and 5 State of West Virginia, have invented certain new and useful Improvements in Gas-Burners; and I do declare the following to be a full, clear, and exact description of the invention, such as will enable others skilled 10 in the art to which it appertains to make and use the same.

This invention relates to improvements in gas burners and more particularly to those designed for use in connection with hot 15 plates and the like.

The primary object of the invention is to provide a burner of this character so constructed that a maximum quantity of air may be fed both with the gas fed to the 20 burner and to the flame while burning, thereby insuring an intense heat and perfect combustion, consuming all the poisonous gas and with a minimum consumption of gas forming the fuel.

Another object is to so construct a burner 25 of this character that the gas will be fed to the mixing chamber of the burner with great force and rapidity, carrying with it a large amount of air and which causes a 30 perfect mixing of the air and gas in its passage to the burner proper.

Another object is to provide a burner having one chamber arranged within the other to cause a second mixing of the air and gas 35 before ignition.

Another object is to provide a burner having a plurality of openings so arranged as to form air inlets for supplying fresh air to the fire while burning, thereby aiding in 40 producing perfect combustion, resulting in a thick jelly-like flame which retains all the poisonous gas and consumes it without permitting any to pass off to the atmosphere.

With these and other objects in view, the 45 invention consists of certain novel features of construction, and the combination and arrangement of parts as will be more fully described and claimed.

In the accompanying drawings: Figure 1 50 represents a plan view of a burner constructed in accordance with this invention; Fig. 2 is a side elevation thereof; Fig. 3 is a longitudinal section thereof taken on the line 3—3 of Fig. 1; Fig. 4 is a transverse 55 section taken on the line 4—4 of Fig. 1, and

Fig. 5 is a detail perspective view of the inner member or casing of the burner.

The improved burner contemplated by the present invention comprises an outer casing 1, here shown cylindrical in form and 60 having closures at both ends, the upper end or top 2 being provided with a plurality of series of perforations 3 laterally spaced and extending transversely across said top, the bottom or lower end thereof being imperforate. The spaces 4 between said series are designed to admit fresh air to the burning gas which passes through these perforations, said perforations being designed as discharge gas outlets for the burner. 65 Disposed in this cylindrical casing 1 is an inner casing 5 which rests on the bottom of casing 1 and is here shown provided with straight side walls 6 and curved ends 7 which latter are shaped to conform to the 70 inner faces of the cylindrical side walls of the casing 1 and to fit closely against said walls, said curved walls forming the end closures for the inner casing. The side walls 6 of this inner casing 5 are provided 75 with openings 8 which are here shown arranged at diametrically opposite points and of inverted V-shape, but they may be of other configuration if desired.

As shown, the bottom of the inner casing 85 5 is formed by the bottom of the outer casing, the side walls of said inner casing having outwardly extending flanges 9 on their lower edges which are secured to the bottoms in any suitable manner, preferably 90 resting on said outer casing bottom and held by friction in place by the engagement of the ends of the casing with the opposed side walls of the outer casing to provide for the removal of said inner casing when it is desired for cleaning or other purposes. This inner casing 5 is of less height than the outer casing providing a space 10 between 95 its top and the perforated top of the outer casing and which constitutes the fuel chamber of the burner through which the fuel passes previous to its exit through the series of apertures in the top 2 of the outer casing.

The outer casing 1 is provided with oppositely disposed openings 11 formed in the side walls thereof at points opposite the ends of the inner casing 5 and in which are fixed the smaller ends or apices 12 of funnel-shaped inlet members 13, the larger ends or mouths of which extend laterally out- 100 105 110

ward from said casing and their inner ends discharge into the inner casing.

A gas supply pipe 14 is provided with lateral branches 15 having inturned nipples 16 arranged to discharge into the mouths of the funnel-shaped members 13, the discharge apertures therein being so formed that the gas under pressure enters the funnels 13 under great force and very rapidly, thereby drawing with it into said funnels a large quantity of air sucked in from the surrounding atmosphere and the air and gas passed together into the mixing chamber formed inside the inner casing 5 where the initial mixing of the air and gas occurs. The gas and air mixed in this chamber or casing 5 passes out from the opposite sides thereof through the V-shaped openings 8 into the outer casing and passes up over the inner casing into the space 10 between the top of said casing and the top 2 of the outer casing, and from thence it passes through the burner openings formed by the series of apertures 3 arranged in rows across the top 2 and spaced laterally apart where the gas is ignited and forms the heating flame. The air which is sucked in between the series of openings also mixes with the burning gas and forms a thick jelly-like flame which resembles quivering hot lead being a thick body of fire and not a thin sheet of flame as is ordinarily produced. The advantage of this thick jelly-like flame is that it retains all the poisonous gas and destroys it, not allowing it to escape into the surrounding atmosphere and thereby rendering the burner especially desirable for use where no escape pipe is provided for obnoxious gases.

In burners ordinarily employed, the more gas that is fed to the burner the higher the flame produced, while with this peculiarly constructed burner, the flame thickens and is produced by the large quantity of air mixed with the gas as it passes into the burner and as it passes out of the burner, air inlets being provided by the spaces 4 between the flames or rows of fire on top of the burner.

This burner may be supported in any suitable manner as may also the funnel-shaped inlet members therefor, said members being here shown connected with the branch pipes 15 by plates 17 secured to the funnels and to said pipes.

I claim as my invention:

1. A gas burner comprising one chamber disposed within another, the inner chamber having outlet openings in opposite side walls and inlet openings arranged in its side walls in planes at right angles to the planes of the outlet openings, funnel-shaped inlet members arranged outside said outer chamber and having the apices thereof extending through the walls of said outer chamber into the inner chamber, and gas nipples discharging into the mouths of said funnel-shaped members, the top of said outer chamber being disposed above that of the inner chamber and having fuel outlet openings 70 therein.

2. In a gas burner, the combination of a closed cylindrical outer casing, an inner casing disposed therein and having straight side walls and curved ends conforming to the curvature of and fitting the opposed inner faces of the outer casing, said inner casing being of less height than the outer casing, funnel-shaped inlet pipes arranged outside the outer casing and having their apices extending through the side walls of the outer casing and opening into the ends of the inner casing, the side walls of said inner casing having openings therein and the top of said outer casing having laterally spaced series of fuel outlet apertures arranged thereacross.

3. In a gas burner, the combination of a closed cylindrical outer casing, an inner casing disposed therein and having straight side walls, and curved ends conforming to the curvature of and fitting the opposed faces of the outer casing, said inner casing being of less height than the outer casing, funnel-shaped inlet pipes arranged outside the outer casing and having their apices extending through the side walls of the outer casing and opening into the ends of the inner casing, the side walls of said inner casing having inverted V-shaped openings 100 therein at their lower edges, and the top of said outer casing having laterally spaced series of fuel outlet openings.

In testimony whereof I have hereunto set my hand in presence of two subscribing 105 witnesses.

BENJAMIN CAVEN BARTLEBAUGH.
